DESIGN FOR A CUFF LINK

Viola T. Howard, Saylesville, R. I., assignor to
The Baer & Wilde Co., Inc., a corporation of Massachusetts

Application January 24, 1936, Serial No. 60,763

Term of patent 3½ years

To all whom it may concern:

Be it known that I, Viola T. Howard, a citizen of the United States of America, residing at Saylesville, county of Providence, State of Rhode Island, have invented a new, original, and ornamental Design for a Cuff Link, of which the following is a specification, reference being had to the accompanying drawing forming a part thereof;

Fig. 1 is a perspective view of a cuff link, showing my new design; and Fig. 2 is a top plan view, of the same.

I claim:

The ornamental design for a cuff link, substantially as shown.

VIOLA T. HOWARD.
